INVENTOR.
George S. Hall
BY *George S. Hall*
ATTORNEY

UNITED STATES PATENT OFFICE.

GEORGE S. HALL, OF CHICO, CALIFORNIA.

RADIATOR-TESTING APPARATUS.

Application filed April 30, 1921. Serial No. 465,651.

To all whom it may concern:

Be it known that I, GEORGE S. HALL, a citizen of the United States, residing at Chico, county of Butte, State of California, 5 have invented certain new and useful Improvements in Radiator-Testing Apparatus; and I do declare the following to be a full, clear, and exact description of the same, reference being had to the accompanying 10 drawings, and to the characters of reference marked thereon, which form a part of this application.

This invention relates to improvements in apparatus for testing automobile radiators 15 for leaks, and is particularly an improvement over that form of apparatus shown in my application for Patent, Serial No. 344,505, filed December 13th, 1919, and allowed January 18th, 1921, the principal 20 object of the present invention being to simplify and render more substantial, the mechanism for raising the table which supports the radiator, so that very little if any wear will be had even after long usage, and 25 the well containing such mechanism may be very easily cleaned out when the occasion arises.

The above objects I accomplish by means 30 of such structure and relative arrangement of parts as will fully appear by a perusal of the following specification and claims.

In the drawings similar characters of 35 reference indicate corresponding parts in the several views.

Fig. 1 is a sectional elevation through the 40 tank and well, showing the table raising mechanism.

Fig. 2 is a cross section taken on a line 2-2 of Fig. 1.

Fig. 3 is a top plan view of the table.

Referring now more particularly to the characters of reference on the drawings, the 45 numeral 1 denotes the tank, of suitable dimensions as to depth, width and length, so as to accommodate, and enable to be completely submerged under the water carried in the tank, a radiator of any size. Depending downwardly from the tank and preferably positioned centrally thereof is a well 50 2, closed on the bottom, but open on top and preferably rectangular in cross section, being arranged to receive and form a guide for a rack bar 3 whose teeth 3^a mesh with a pinion 4 positioned in a pocket 5 at the

upper end of the guide well, this pocket being integral with the well. 55

The shaft 6 of the pinion is journaled in bosses 7 formed with the pocket walls, one boss being blind-bored while the other being provided with a form of stuffing box 8 through which the shaft projects. The outer end of the shaft is provided with a hand-wheel 9 to turn the same, and also with a ratchet wheel 10 therebehind, the pawl 11 for said ratchet being fixed on the frame or 60 table 12 on which the tank is supported. The pawl and ratchet are of course positioned to prevent undesired downward movement of the rack-bar. 65

The lower end of the well is provided with 70 a drain plug 13, and the lower end of the rack with a block of rubber 14 or some similar material, to absorb the shock in the event that the rack should tend to strike the bottom of the well. 75

On top of the well is a flange 2^a, resting on the bottom of the tank and making a watertight connection therewith. Seated in the upper end of the well is a cover or cap 15 provided with a flange 15^a resting on the 80 flange 2^a, so that while the cover may be withdrawn from the well by raising it, its weight keeps it in position and it cannot have lateral movement, even without fastenings. 85

This cap is provided with an orifice 16 through which the rack passes, thereby forming an additional guide for the rack when the latter is raised a considerable distance, and also serves to prevent the unavoidable 90 sediment or foreign matter in the water from passing into the well in any appreciable quantity, which would very likely cause a clogging of the gear teeth sooner or later. At the same time it may be easily removed 95 when cleaning is necessary.

The rack 3 supports a table 17 preferably made up of piping and connections to form a cross as at 18, there being a circular band 19 fixed to the outer ends of the arms of 100 the cross. A pin 20 is fixed to the table centrally thereof, and is turnably mounted in the top of the rack.

In operation, the radiator to be tested for 105 leaks is placed on the table, and then submerged under the water in the tank by releasing the pawl which controls the downward movement of the rack. A supply of

compressed air is of course operated in connection with the radiator to fill the passages of the same, as was set forth in the application hereinbefore mentioned.

5 From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 15 claims.

Having thus described my invention, what I claim as new and useful and desire to secure by Letters Patent is:

1. An apparatus for testing radiators comprising a tank, a well depending therefrom, 20 a bar slidably mounted in the well and provided with means for supporting a radiator, rack teeth on the bar, a pinion meshing with said teeth and journaled in the well,

a shaft fixed to the pinion and projecting 25 from the well, and packing means about the shaft where it emerges from said well.

2. An apparatus for testing radiators comprising a tank, a well depending therefrom, 30 a bar having a working fit in the well slideable therein, a rotatable table supported by the bar, rack teeth on the bar, a pinion meshing with said teeth and journaled in the well and hand actuated means for rotating said pinion from the exterior of the well. 35

3. An apparatus for testing radiators comprising a tank, a well depending therefrom, 40 a bar having a working fit in the well slideable therein, a rotatable table supported by the bar, rack teeth on the bar, a pinion meshing with said teeth and journaled in the well adjacent the top thereof, a removable cover fitted over the well inside the tank and provided with an orifice to guide the bar, and hand actuated means for rotat- 45 ing the pinion.

In testimony whereof I affix my signature.

GEORGE S. HALL.
